UNITED STATES PATENT OFFICE.

WILLIAM C. HEITKAMP, OF PLEASANT RIDGE, OHIO.

SMOOTH-BORE ROTATING CANNON.

No. 819,995.

Specification of Letters Patent.

Patented May 8, 1906.

Application filed August 3, 1904. Serial No. 219,378.

To all whom it may concern:

Be it known that I, WILLIAM C. HEITKAMP, a citizen of the United States, residing at Pleasant Ridge, in the county of Hamilton and State of Ohio, have invented a new and useful Improvement in Smooth-Bore Rotating Cannon, of which the following is a specification:

This invention is an improved construction of cannon or gun, the object of the invention being to provide a smooth-bore cannon which will rotate the projectile as it passes through the barrel, thereby imparting to said projectile a rotary motion similar to that imparted by a rifled cannon or gun.

The cannon or gun constructed in accordance with my invention can be made much quicker and easier, inasmuch as the rifling operation, which is slow and expensive, is entirely avoided.

Broadly speaking, my invention consists in making the cannon of an outer section and an inner section, said inner section having a series of spirally-arranged grooves upon the exterior thereof, each groove having an inlet-opening at its rear end and which communicates with the bore of the cannon and the outlet-opening at the forward end, which also communicates with the bore of the cannon, said grooves and passages being so arranged that the gases generated in the explosion-chamber will pass therethrough simultaneously with the passage of the projectile and owing to the spiral arrangement of the grooves and passages will impart a rotary motion to the projectile as it passes through the bore of the cannon.

The invention consists also in certain details of construction hereinafter fully described, and pointed out in the claims.

In the drawings forming a part of this specification, Figure 1 is a diagrammatic sectional view illustrating my invention. Fig. 2 is a top plan view of the inner section of the cannon looking in the direction of the arrow 1 of Fig. 4. Fig. 3 is a side view of said section looking in the direction of arrow 2 in Fig. 4. Figs. 4, 5, and 6 are transverse sectional views of the inner section of the cannon, taken on the lines 4 4, 5 5, and 6 6 of Fig. 2.

In constructing a cannon in accordance with my invention I employ an outer section A, which may be constructed in any suitable

manner and provided with any suitable form of breech mechanism.

B indicates an inner tubular section, which fits snugly within the outer section, and upon its exterior is provided with a series of grooves C, said grooves being arranged upon spiral lines, as most clearly shown in Figs. 2 and 3. Each groove has an inlet-passage D leading from its rear end into the interior of the tubular section B, and each tube also has an outlet-passage E leading from its forward end into the interior of the tubular section B.

By reference to Fig. 1 it will be noted that when the charge is fired a portion of the gases will pass into the passages D through the grooves C and out through the passages E back into the interior of the tubular section B, and owing to the spiral arrangement of the grooves C a whirling current or, in fact, a series of whirling currents will be produced in the barrel of the gun, which will act upon the projectile as it passes through the said barrel, and in this manner a rotating motion is imparted to said projectile substantially the same as though the barrel of the gun were rifled. Inasmuch as the inner tubular section B fits snugly within the outer section A the grooves C, together with the passages D and E, form continuous passages spirally arranged, as shown, and it will be noted that these spirally-arranged passages gradually increase in length toward the muzzle of the gun, inasmuch as the projectile is traveling faster at the muzzle than at the breech of the gun.

It will thus be seen that I provide an exceedingly cheap simple construction of smooth-bore cannon which will produce exactly the same result as a rifled cannon, and it will also be noted that this result is accomplished without weakening said cannon.

Having thus fully described my invention, what I claim as new, and desire to secure by Letters Patent, is—

1. A smooth-bore cannon having a series of gas-passages spirally arranged with reference to the bore of the cannon, and communicating at their ends with the said bore.

2. A smooth-bore cannon comprising inner and outer tubular sections and having a series of curved gas-passages arranged spirally with reference to the bore, the ends of said passages communicating with the bore of the cannon.

3. A smooth-bore cannon having a series of spirally-extending gas-passages, the ends of which communicate with the bore of the cannon, said gas-passages being graduated as specified.

4. A smooth-bore cannon comprising the inner and outer tubular sections, the inner tubular section having a series of grooves upon the exterior thereof, each groove being 10 spiral relative to the bore and having an in-

let-passage communicating at its rear end with the bore, and an outlet-passage communicating at its forward end with the bore, said grooves being graduated in length as specified.

WILLIAM C. HEITKAMP.
